[57] CLAIM

The ornamental design for an aerosol dispenser unit for attachment to a toilet seat, as shown and described.

DESCRIPTION

FIG. 1 is a perspective view of an aerosol dispenser unit for attachment to a toilet seat showing my new design; FIG. 2 is a front elevation view thereof; FIG. 3 is a right side elevation view, the left side being a mirror image thereof; FIG. 4 is a rear elevation view thereof; FIG. 5 is a top plan view thereof; and FIG. 6 is a bottom plan view thereof.
